To all whom it may concern:

Be it known that we, Porter H. Mason, William D. Mason, and Jack H. Mason, all citizens of the United States, residing at Norfolk, in the State of Virginia, have invented a new, original, and ornamental Design for a Stencil Duplicator, of which the following is a specification, reference being had to the accompanying drawing, forming part thereof.

Figure 1 is a perspective view of a stencil duplicator, showing our new design;

Figure 2 is a view in side elevation;

Figure 3 is an end view;

Figure 4 is a top plan view; and

Figure 5 is a bottom plan view.

We claim:

The ornamental design for a stencil duplicator,
as shown.

PORTER H. MASON.
WILLIAM D. MASON.
JACK H. MASON.
